UNITED STATES PATENT OFFICE

144,479

DESIGN FOR A CIGARETTE CASE

George H. Bugenhagen, Midland, Mich.

Application November 5, 1945, Serial No. 123,475

Term of patent 7 years

(Cl. D85—2)

To all whom it may concern:

Be it known that I, George H. Bugenhagen, a citizen of the United States and a resident of Midland, in the county of Midland and State of Michigan, have invented the new, original, and ornamental Design for Cigarette Cases, of which the following is a specification, reference is had to the accompanying drawing, forming part thereof, in which:

I claim:

The ornamental design for a cigarette case, as shown.

GEORGE H. BUGENHAGEN.
